CALCULATING MACHINE

Grant C. Ellerbeck, San Leandro, Calif., assignor to
Friden Calculating Machine Co., Inc., a corporation
of California

Application October 5, 1953, Serial No. 384,053

7 Claims. (Cl. 235—138)

This invention relates to calculating machines and is especially concerned with an improved mechanism for actuating the counter register.

A primary object of the present invention is to provide an improved actuator for the counter mechanism shown and described in the patent to Carl M. Friden, No. 2,229,889, of January 28, 1941.

An important object of the present invention is to provide a counter actuator in which it is unnecessary to stagger the tens-transfer mechanism connected therewith. In the conventional counter mechanism, such as disclosed in the patent above-mentioned, the tens-carry mechanisms associated with the counter actuator are staggered around an operating shaft so that a transfer wave (i. e., a transfer through a plurality of orders as is required when the counter stands with a plurality of consecutive "9's" and the lower one is moved from "9" to "0") may occur. It will be understood that the transfer mechanism must be conditioned for the transfer from the lower order to its adjacent higher order prior to conditioning the transfer mechanism from the adjacent order to the next higher order, etc. In my invention the transfer mechanism can be arranged on substantially the same plane, which results in considerable saving in assembly, as in conventional mechanisms the transfer devices must be accurately staggered around the control shaft in order to accommodate the transfer wave.

Still a further object of the present invention is to provide a more efficient transfer actuator and tens-transfer mechanism for a counter register.

These and further objects of the present invention will be fully understood from a reference to the following specification and claims, and they, in turn, will be more readily understood by a reference to the drawings, in which:

Fig. 1 is a left side view of a portion of the control mechanism associated with my invention.

Fig. 2 is a left side view of another control mechanism for the counter actuator.

Fig. 3 is a plan view of the mechanism shown in Fig. 2.

Fig. 4 is a front view of four orders of a counter mechanism of the type generally described in the patent above-mentioned.

Fig. 5 is an end view of one of the actuators above the lowest order, showing the transfer mechanism in its full-cycle or neutral position.

Fig. 6 is an end view similar to Fig. 5, but showing one of the transfer devices in its operative position.

Fig. 7 is a detailed right end view of a means for rocking camming bail 84, such as a view taken along the vertical plane indicated by the line 7—7 of Fig. 4.

The machine with which the present invention is preferably associated, is similar in construction to that described in the above-mentioned patent. Therefore, reference is made to that patent for the general construction of the calculating machine. It can be mentioned that the machine includes a pair of frame plates, a right side frame plate 10 (shown in Figs. 2, 3 and 4) and a left frame

2

plate 11 (shown in Fig. 1). The frame plates are interconnected to form a rigid structure by various crossbars, not here pertinent, and a carriage rail 12 (shown in Figs. 1, 2, 5 and 6). This machine also includes a laterally shiftable carriage which supports the accumulator register (neither of which is shown), and the counter register which includes the counter dials 20. The counter dials are mounted on parallel, longitudinally extending shafts 21, the front ends of which are journaled in a front carriage bar 22 (Figs. 5 and 6). It will be understood that the dials 20 carry the numerals from "0" to "9," inclusive, which numerals are viewable through suitable windows in the carriage cover (not shown herein). It will also be understood that the numeral wheels, or dials, 20 are centralized in proper position and can simultaneously be cleared to "0" by conventional mechanisms (not here pertinent).

A flanged sleeve 23 is also rigidly mounted on each of the countershafts 21, forwardly of the dial 20, as shown in Figs. 5 and 6. The rearward flange of the flange sleeve 23 is cut as a 10-tooth gear 24, while the forward flange, or disk, 25 is provided with a single notch 26. The notch 26 in the disk 25 is so located, with respect to the "9" position of the dial 20, that it (the notch) lies adjacent the actuator, next to be described, when the latter is in operating position in addition, and "9" shows through its window. The notches 26 are shown in the "0" position in Fig. 4, in which position they will be engaged by the counter actuators, next to be described, in a subtraction cycle.

The counter dial 20 aligned with the units order of the machine is given a single step of rotation, with each machine cycle, in order to provide a counter of "1," additively or subtractively, with each cycle of machine operation. This cycle step-by-step movement is provided by an actuator which is mounted on a counter actuator shaft 30 mounted in the side frames 10 and 11 for rotational and for longitudinal movement. The actuator, including the shaft 30, is given a compound motion having two major components: one a translatory reciprocation and the other a rotary oscillation. It can be mentioned that when the counter is operated in an additive direction the shaft is first rocked (clockwise in Figs. 5 and 6) then shifted to the left, then rocked back to its original angular position and finally shifted to the right to the home position. Conversely, when the value is being entered subtractively, the shaft is first shifted to the left, then rocked into engagement with the counter (clockwise in Figs. 5 and 6), then shifted to the right, and finally rocked back to the starting position. Thus, the counter mechanism rocks through the same path regardless of whether values are being entered additively or subtractively—the difference between the two operations being the result of the difference in timing of the rocking and translatory movements. Mounted on the shaft 30, and adjacent the ends thereof, is a pair of two-armed members 31 (see Figs. 5 and 6) which support a pair of substantially diametrically opposed parallel rods 32 and 33. The rearward rod 32 serves as a spring seat as will hereafter be described, and can be rigidly mounted in the supporting arms 31. The forward rod 33, on the other hand, in my invention, should be rotatably mounted in the members 31.

A plurality of actuator spools 40 are rotatably disposed along the shaft 30, between the rods 32 and 33. These actuator spools 40 are of identical size and shape, with the exception of the right-hand, or lowest order, actuator 41, and are of a length equal to the ordinal spacing of the shafts 21. It can be noted that all of the spools 40 (except the actuator spool 41 in the right-hand, or lowest order) are operative only for transfer actuation; while the right-hand spool 41 is cyclically operable to effect the count into the aligned counter dial 20. This right-

hand, or lowest order, spool 41 (as seen in Fig. 4), is only partially complete as compared with the other spools 40, and carries a finger 42 on its left end (which finger 42 is also mounted on the left end of each of the spools 40). This finger 42 is adapted, upon rotation of the spools 41 or 40, to rock between the teeth of the 10-tooth gear 24. An eyelet 43 is formed in the finger 42, which eyelet serves as a seat for one end of a small spring 44 tensioned between the finger 42 and the rear transverse rod 32. Thus, the cyclic rocking of the actuator shaft 30 and the members 31, resiliently biases the fingers 42 into engagement with their respective gears 24.

The right end of each of the higher order spools 40 is provided with a second finger 45. This last-mentioned finger 45 is angularly disposed on the spool 40 forwardly (to the left in Figs. 5 and 6) of the counting finger 42 and is formed, or bent, so that its circumferential extremity will lie in the plane of the counting finger 42 of the next lower order. The last-mentioned finger 45 is adapted to intersect the slot 26 in the disk 25 of the lower order, when a tens-transfer is required. However, if the slot or notch 26 is not in a position to be intersected by the finger 45 when the shaft 30 is first rocked, then the rotation of the finger is blocked by the solid face of the disk 25 to prevent a transfer from occurring in the associated and all higher orders.

As mentioned before, the shaft 30 is rocked and shifted axially in a timed sequence in each cycle of machine operation (the time of rocking in the program depending upon whether the entry of a value into the counter is additive or subtractive). The rocking of the shaft 30 causes the rocking of the members 31 which are rigidly secured thereto, and consequently the two connecting bars 32 and 33 are likewise invariably rocked, or rotated. Rocking of the bar 32 (by means of the resilient tension of spring 44), resiliently biases all of the sleeves 40 and 41 first clockwise, and then, later the forward bar 33 returns them counter-clockwise to their original position. The clockwise rocking of the higher order sleeves 40 which, if permitted, will cause the fingers 42 to engage the teeth of the ordinally associated gears 24, is necessarily resilient, so as to permit the counting finger 42 to be blocked short of engagement with the gear in order to prevent a count when that is necessary. It will be understood that normally the rocking of the counting finger 42 is blocked by its sensing finger 45 engaging the disk 25 of the adjacent lower order, for they must not operate their related gears 24 except when a transfer occurs from the next lower order.

It can be mentioned at this point that means are conventionally provided to block operation of the units order sleeve 41 in certain automatic operations, or at the will of the operator, by means not here pertinent. For the purpose of my invention, therefore, it will be assumed that the units order sleeve 41 will be operative with each cycle of machine operation and will therefore be effective to enter a value of "1" additively or subtractively into the counter dial 20 aligned therewith. If the notch 26 is in line with the finger 42 of the units order actuator sleeve 41, when the shaft 30 is first rocked, then the tens-transfer finger 45 of the second, or next higher, order (which is also resiliently rocked clockwise by the force of its spring 44) will enter the slot 26 of the first order, thereby permitting sleeve 40 of the second order to rock clockwise with the rocking of shaft 30. In that event, the counting finger 42 of the second order sleeve 40 can mesh with the teeth of the gear 24 of the second higher order dial 20. Then, when the shaft 30 is translated longitudinally to enter the count in the lower order dial, the next higher order dial will also be operated by its spool 40. However, if the notch 26 of the dial aligned with the units order spool 41 is not in a position to be intersected by the resilient rocking of the transfer finger 45, then that finger will engage the sur-

face of the disk 25 which blocks further rocking thereof. Such blocking of rotation of the second order sleeve 40 will prevent its counting finger 42 on the left end thereof from engaging the teeth of the second order gear 24—thereby blocking the count in that order. By this means a single unit is entered into the counter dial aligned with the units order of the machine, and a transfer (even to the full length of the counter register) can be provided when a transfer is called for.

It will be seen that the rocking of the shaft 30 resiliently urges the respective counting fingers 42 toward meshing engagement with their ordinally related gears 24, through the force of the springs 44. At this juncture the rotary oscillation of the shaft 30 is interrupted and the shaft translated axially (toward the left in addition and toward the right in subtraction). Such movement occurs while the counting fingers 42 remain enmeshed with their ordinally related gears 24, and is therefore effective to rotate the gears, and their shafts 21 for one-tenth of a complete revolution, and thus advance the ordinally related dials 20 one digit.

At the conclusion of such axial movement of the shaft 30, the shaft is again rocked (counter-clockwise in Figs. 5 and 6), so that the finger 42 is rotated out of engagement with its ordinally related gear 24. Normally the release of tension on the springs 44 and the slight drag between the sleeves 40 or 41 and the shaft 30, will cause the sleeves 40 to rock counter-clockwise and therefore disengage the counting teeth from their gears. However, if the drag is not sufficient, the counter-clockwise rocking of the front bar 33 will engage projection 46 on the forward edge of the units order spool 41 to positively rock it to its neutral, or disengaged position. Such rocking of spool 41 positively drives all of the higher order spools to the like position, for rocking of any counting finger 42 (counter-clockwise in Figs. 5 and 6) pushes the sensing finger 45 ahead of it, which is repeated throughout the length of the higher orders.

As previously indicated, if the shaft 30 is initially rotated to mesh the counting fingers 42 with the ordinally related gears 24 and then the shaft translated to the left, the numeral wheel 20 is advanced in a positive, or additive, direction. If, on the other hand, the shaft is first translated to the left and then rocked clockwise, the respective gears will be rotated during the rightward movement of the shaft and the numeral wheels 20 will be rotated in a subtractive, or negative, direction.

If a notch is out of passing position, i. e., when no tens-transfer has been determined by the units and intermediate order counter wheels, the associated transfer-sensing finger 45 cannot pass the barrier of the disk, and the respective spool 40 therefore cannot rotate with shaft 30. Thus, the counting finger 42 of that spool is held out of counting position. Due to the similar interlocking relationship of the higher order spools 40, all of the higher order spools are held in inactive position unless the notch 26 in the units order disk 25, and all intermediate disks are in a transferring position. By this means a transfer is positively effected in all of the higher order dials when the transfer chain is complete to the lowest order, but is blocked whenever it is not.

The means for effecting the necessary operation of the counter shaft 30, i. e., its timed rotation and axial translation, will now be described. It can be mentioned that each type of movement (rotational or translatory) is provided by separate cams 50 and 60 (Figs. 1, 2 and 3, respectively), both of which are mounted on the drive shaft 13 of the machine. Therefore, the program of operations is always in timed relation, as both cams are rigidly secured to the drive shaft 13. The rotational motion of the shaft 30 will first be described. This motion is derived from an internally grooved cam 50 mounted on the left end of the drive shaft 13, as shown in Fig. 1. A groove 51 in the cam provides an eccentric path of travel for a follower stud 52 mounted on one arm of a bellcrank 53.

The bellcrank 53 is pivotally mounted on the left frame plate 11 by any suitable means, such as stud 54. The upper arm of the bellcrank 53 is slotted, as at 55, to embrace a pin 56 carried by an arm 57 rigidly mounted on the shaft 30. The rotation of the drive shaft 13 thus positively rocks the bellcrank 53, and consequently the shaft 30 through a full cycle with each cycle of machine operation. The timing of the rotary oscillation thus provided allows time for a slight dwell to accommodate the first translatory movement of the shaft in a subtractive operation, and then causes engagement of the counter finger 42 with its associated gear 24 by the first phase of such rotary oscillation, which occurs during the first part of the cycle. Then a dwell occurs in such rotary oscillation while the engagement of the finger and gear is maintained to allow for the axial translation to cause movement of the gear for one tooth space. Subsequently the finger is disengaged from the gear by the last phase of the rotary oscillation, the disengagement being effected before the end of the cycle to allow time for the second half or phase of the axial translation to return the actuator finger to its starting position, in additive operation.

The longitudinal, or axial, translation of the shaft 30 is provided by a mechanism shown particularly in Figs. 2 and 3. The movement is derived from a wobbler cam 60 which is mounted on the drive shaft 13 immediately to the left of the right frame plate 10. The wobbler cam has a pair of grooves 61 and 62 cut therein. These cam grooves are of identical contour but are polarly, or angularly, spaced from each other. In order to change the phase relationship of the axial movement of the shaft 30 to its rotary movement, means is provided for optionally engaging either of the grooves 61 or 62. For this purpose a yoke 63 is provided which is rotatably mounted on a shaft 64 carried by a pair of brackets 65. The lower end of the yoke 63 carries an arm 66, on the outer extremity of which is provided a pin 67 adapted to engage the cam groove 62. The upper end of the yoke is provided with a two-armed lever member 68, on the forward extremity of which is provided a pin 69 which is adapted to engage the cam groove 61. The extremities of the two pins 67 and 69 are spacially arranged so that both may be disengaged from their grooves as the counter is shifted from positive to negative registration, and only one or the other of the pins can be engaged in its groove during operation. The rearward end of the upper arm 68 is provided with an upwardly extending pin 70, which is embraced by the flanges of a flanged collar 71 mounted on the shaft 30. The yoke 63 also carries a flanged collar 72 which embraces a pin 73 mounted on an arm 74, which arm in turn is rigidly mounted on a short shaft 75. Thus, rotation of shaft 75, by any means not here pertinent, is effective to place the yoke 63 in either its elevated position in which the pin 67 on the lower arm 66 engages its groove 62, or the upper pin 69 engages its groove 61 in the wobbler cam. In either position of the yoke 63, it is given an oscillatory movement determined by one of the grooves 61 or 62, depending upon which pin 67 or 69 is engaged with its respective groove. This oscillatory movement is transmitted by the rearward arm of the upper lever 68 to pin 70 which, through its engagement with the flanged collar 71, translates the shaft 30 longitudinally. If the lower pin 67 is in engagement with cam groove 62 then registration in the counter is additive. In this event an initial dwell permits rocking of the shaft 30 by cam 50 to cause meshing of the counter teeth 42 with their respective gears 24, after which the groove 62 rocks the yoke 63 to cause leftward translation of shaft 30; tooth 42 is then disengaged during a short dwell in the cam groove, and at the end of a cycle the cam returns to its full-cycle position and moves the shaft 30 to the right. If on the other hand, the pin 69 is engaged in the groove 61, then registration in the counter is negative. In that event the cam groove immediately rocks the yoke 63 (counter-clockwise in Fig. 3) to translate the shaft 30 to the left at the start

of the cycle of operation; thereafter a dwell in the cam slot 61 holds the yoke 63 stationary while the cam 50 and bellcrank 53 are operative to rock shaft 30 to cause engagement of the counter teeth 42 with their respective gears; and then cam groove 61 returns the yoke 63 and the shaft 32 to their initial, or full-cycle, axial position, after which a dwell in slot 62 holds the yoke stationary while the cam 50 causes disengagement of the counter teeth 42 from their respective gears. Thus, as the main drive shaft 13 rotates, it imparts to the shaft 30 an axial translation in either selected one of two different phase relationships with the driving shaft. This phase relationship, which is selected in particular instances, controls the sign character of registration on the numeral wheels 20 of the revolutions counter as outlined above.

It is desirable, in the counter mechanism described in the patent above-referred to, to slightly stagger the counting fingers 42 in order to enable a transfer wave to proceed from right to left in all instances. In usual shop practice, it is conventional to make the parts identical, and then have a mechanic adjust the assembled mechanism by bending the fingers 42 inwardly (counter-clockwise in Figs. 5 and 6) to provide a stagger of about .012 inch between orders. Such staggering also adjusts the sensing fingers 45 so that the lower order sensing finger either starts to penetrate the associated slot 26 or is blocked before the next higher sensing finger will engage its disc, so only one finger will engage its disk in any cycle. This staggering requires extreme accuracy in the formation of the parts and considerable time in assembling the mechanism. I am able to avoid both of these difficulties by means of the mechanism of my invention which will now be described.

I provide each of the higher order actuating sleeves 40 with a forwardly extending and pointed cam nose 80. These noses can be mounted on any part of the sleeve 40, but for convenience I have formed them as a projection integral with the counting finger 42. These forwardly projecting fingers 80 are provided with a relatively sharp point 81, an upper concave cam surface 82, and a lower convex cam surface 83, as shown in Figs. 5 and 6. Associated with the cam projections 80 is a transversely extending camming bail 84, which is mounted in the lower ends of a plurality of arms 85 rigidly mounted on the front shaft 33.

As the shaft 30 and its integral arms 31 are rocked, the bail 84 will be lifted to the position indicated by 84A in Fig. 5 by the time the transfer control finger 45 will have started to penetrate the related notch 26. If the transfer finger 45 has come into engagement with the surface of the disk 25, the cam nose 80 will have rocked to the position indicated by 81A in Fig. 5 and further rotation is thereupon blocked. If, on the other hand, the transfer finger 45 has entered a notch 26, the sleeve 40 will rock a slightly greater distance, as to the position indicated by 81B in Fig. 5.

At this point the shaft 33 is given a sharp rotational movement by a means next to be described (counter-clockwise in Figs. 5 and 6), which movement rocks the bail 84 into engagement with the cam projections 80. As indicated in Fig. 5, the bail will engage the upper cam face 82 if rocking of the sleeve has been blocked by the disk 25 and will engage the lower cam face 83 if the transfer finger 45 has entered the notch 26. In the first event the sleeve is given a slight counter-clockwise rotation to back the transfer finger 45 away from the disk and in the latter case the sleeve 40 is given a slight clockwise rotation to positively engage the counting finger 42 in the gear 24. In the first instance the transfer actuator sleeves 40 are backed away from engagement with their related dials and in the second instance they are positively forced into a better engagement therewith.

The slight rocking of the shaft 33 can be secured by a variety of means, one of the simplest of which is shown in Figs. 4 and 7. In this embodiment an arm 90 is rigidly

secured to the right end of the shaft 33. This arm carries a pin 91 which penetrates a shaped aperture 92 in the right side frame plate 10. As shown in Fig. 7, the aperture is formed of intersecting arcuately shaped slots which enable the pin to rise with the shaft 33 for a slight distance; after which it engages the upper wall of the slot. The further rotation of the shaft 33 (clockwise in Figs. 5, 6 and 7) cams the pin 91 rearwardly (counter-clockwise as seen in Fig. 7), thereby rocking the shaft 33 and the bail 84 counter-clockwise as previously described.

It would be readily apparent to those skilled in the art that the bail 84 could be mounted on a pair of arms pivoted in the frame of the machine, which arms could be driven by a cam mounted on the drive shaft to secure a rocking of the bail similar to that above-described. Thus, the form of the bail, and the particular method of operating it, is not particularly important. What is important is that the bail be so located that it will lie opposite the space between the points 81A and 81B when the sleeves 40 are blocked or permitted to rock by the disk 25, after which it is given counter-clockwise rotation to cam the sleeves 40 into their extreme adjusted positions shown in Fig. 6.

I have found that a counter actuator constructed in accordance with my invention herein described will operate with extreme accuracy even though made from parts manufactured by conventional shop practices and allowing for conventional tolerances. Further, the counter actuator does not require the accurate assembly, or the accurate staggering of the counter fingers 42 previously required. Thus, my invention provides a counting mechanism which is more efficiently and economically manufactured and assembled, and which gives accuracy equal to, if not exceeding that of, heretofore known counting mechanisms of this kind.

I claim:

1. A counter mechanism for a counter register comprising a plurality of ordinarily arranged counting members, resiliently urged transfer means for operating said counting members, means connected to said counting members for determining a tens-transfer or non-transfer condition of the adjacent lower order, means controlled by said determining means for moving said transfer means toward either an operating or a non-operating position, means including a cam on each of said transfer means and an operating member cooperating therewith for positively positioning said transfer means in either extreme position, and means for operating said operating member.

2. In a counter of the class described having a plurality of ordinarily arranged counter dials, a plurality of ordinarily arranged dial operating members, means for resiliently operating said operating members, means for blocking operation of such members, means for determining a tens-transfer from the adjacent lower order, and means controlled by said determining means for controlling operation of said blocking means, the improvement which comprises cam projections on such members, a bail movable in a path to move said cam projections in one direction if operation of the counting members is blocked and in the other direction if rotation is permitted, and means for moving said bail in said path.

3. In a counter of the class described having a plurality of ordinarily arranged counter dials, a gear operatively connected to each dial, a plurality of ordinarily arranged gear operating members, means for resiliently rotating said operating members into engagement with their respective gears and then axially translating the members, means for sensing a tens-transfer condition in the adjacent lower order, and means operated by said sensing means when sensing a non-transfer condition for blocking rotation of such members, the combination which comprises cam projections on such members, a bail movable in a path to pass on one side of said cam projections if rotation of the counting members is blocked

and on the other side thereof if rotation is permitted, and means for moving said bail in said path.

4. In a counting mechanism comprising ordinarily arranged register dials, a gear and a notched disk affixed to said dials, a counter actuator comprising a rotatable and longitudinally movable shaft, means for rocking and longitudinally moving said shaft, dial operating members rotatably mounted on said shaft, said dial operating members having one portion engageable with the ordinarily related gear and another portion engageable with the disk of the next lower order, means for resiliently rocking said dial operating members from the rocking of said shaft, cam projections on said counting members, a bail mounted for movement in a path to pass on one side of said cam projections when rocking of the dial operating member is blocked by engagement of the second portion thereof with the disk of the next lower order and passing on the other side of said cam projections when said second portion of said dial operating member penetrates the notch in said disk, and means for rocking said bail in said path.

5. In a counting mechanism comprising ordinarily arranged register dials, a gear and a notched disk operatively connected to said dials, a counter actuator comprising a rotatable and longitudinally movable shaft, ordinarily arranged dial operating members rotatably mounted on said shaft, said dial operating members having one portion engageable with the gear of the ordinarily related register dial and another portion engageable with the disk of the next lower order register dial, means for resiliently connecting said dial operating members to said shaft, opposed cam faces on said dial operating members, a bail mounted for movement in a path to engage one face of said cam when the second portion of the dial operating member engages the face of the disk of the next lower order and the opposing face of said cam when said second portion engages the notch in said disk, thereby camming said dial operating members out of or into engagement with said disk and gear, and means for rocking said bail in said path.

6. In a counting mechanism comprising ordinarily arranged register dials, a gear and a notched disk attached to said dial, a counter actuator comprising a rotatable and longitudinally movable shaft, means for cyclically rocking and longitudinally moving said shaft, ordinarily arranged dial operating members rotatably mounted on said shaft, said dial operating members having one portion engageable with the ordinarily related gear and another portion engageable with the disk of the next lower order dial, means for resiliently rocking said dial operating members by the rocking of said shaft, a cam nose on said counting members, a cyclically operated bail cooperating with said cam noses, said bail in its movement engaging one edge of a cam nose when rocking of the dial operating member causes the second portion thereof to engage the face of disks of the next lower order and thereupon cam the counting member in the opposite direction to disengage the disk, and engaging the other edge of a cam nose when rocking of the dial operating member causes the second portion thereof to engage the notch in said disk and thereupon cam the counting member the direction to cause it to engage its gear, and means for rocking said bail.

7. In a calculating machine, a revolutions counter comprising a plurality of ordinarily arranged dials, a gear and a notched disk operatively connected to each dial, the axis of rotation of said gears being disposed parallel in the same plane, a cyclically operable actuator for said counter mounted for axial reciprocation and for oscillation about its axis, the axis of said actuator being disposed transversely with respect to the axis of rotation of said counter gears, said actuators having one portion engageable with the ordinarily related gear and

another portion engageable with the disk of the next lower order, a cam nose on said actuators, a cyclically operated bail movable in a path to pass on one side of said cam projections if rotation of the actuator is blocked and on the other side thereof if rotation is permitted, thereby camming said actuator to an extreme inoperative posi-

tion or an extreme operative position, respectively, and means for moving said bail in said path.
